(57) **CLAIM**

The ornamental design for a fire pit stand, as shown and described.

DESCRIPTION

FIG. 1 is a bottom perspective view of a fire pit stand showing our new design.

FIG. 2 is a top perspective view of the fire pit stand as shown in FIG. 1.

FIG. 3 is a bottom perspective view of the fire pit stand as shown in FIG. 1.

FIG. 4 is a front view of the fire pit stand as shown in FIG. 1.

FIG. 5 is a right side elevation view of the fire pit stand as shown in FIG. 1.

FIG. 6 is a rear view of the fire pit stand as shown in FIG. 1.

FIG. 7 is a left side elevation view of the fire pit stand as shown in FIG. 1.

FIG. 8 is a top plan view of the fire pit stand as shown in FIG. 1; and,

FIG. 9 is a bottom plan view of the fire pit stand as shown in FIG. 1.

In the drawings the broken lines in FIG. 1 depicting a fire pit are illustrating environment and the broken lines in FIGS. 1-7 are shown for the purpose of illustrating parts of the fire pit stand that form no part of the claimed design.
